[57] CLAIM

The ornamental design for a table, as shown and described.

DESCRIPTION

FIG. 1 is a perspective view of a table showing my new design;

FIG. 2 is a front elevational view thereof;

FIG. 3 is a rear elevational view thereof;

FIG. 4 is a side elevational view thereof, the opposite side being substantially the same in appearance; and

FIG. 5 is a bottom plan view thereof.

Stippling is used in the drawings for configuration clarity only.

FIG. 2

FIG. 3

FIG. 5
